corporation of Delaware

Application July 11, 1933, Serial No. 679,916

16 Claims. (Cl. 179—171)

This invention relates to the art of signalling by means of high frequency oscillations, the character of which varies in accordance with signals, and more in particular with a method of and means for displacing the phase of high frequency oscillations in a correct relationship to an applied signal voltage, thereby producing a signal so modulated that intelligent transmission may be made by using phase modulation.

10 In the usual method of modulating the output current of a transmitter the amplitude of the oscillations is made to vary in accordance with the signal to be transmitted. When the input signal is of low amplitude, so that a low percentage of modulation of the carriers is accomplished, the output of the transmitter is less than when the signal is of high amplitude and a larger percentage of modulation is impressed on the carrier. With amplitude modulation the transmitter must be operated below full power output to be able to follow the signal modulation to its peak value. When using amplitude modulation the power output of the transmitter varies in accordance with the percent modulation. In order that the transmitter 20 may be capable of carrying full output on high percent of modulation it must be run at a value below its full output rating on the average modulation. For example, when a broadcast program is sent out over the usual broadcast transmitter the average modulation is about 30%. The transmitter must be so adjusted that while it only delivers a small amount of its power on the average modulation it can 30 carry the peaks or the louder parts of the signal without distortion. Thus the transmitter must be operated below its full output most of the time and less power is radiated than would be possible with this transmitter. In phase 35 modulation, however, the phase relation of the carrier and the sidebands varies in such a manner that the resultant output remains substantially constant. In phase modulation the output of the transmitter remains substantially 40 constant and the modulation sidebands and carrier vary in such a manner that the output energy remains substantially constant. A phase modulated transmitter may be operated at maximum output constantly. This results 45 in increased efficiency and permits more radiation power when using equipment of the same power rating. The oscillations modulated in phase as indicated above may be altered in characteristics at signal frequency in any of 50 the succeeding stages prior to transmission.

The character of the phase modulated wave may be altered as to amplitude, or phase or frequency, or in one or more of said respects.

In the usual type of phase modulation transmitters, elaborate equipment is needed to produce quality of modulation. 5

An object of the present invention is to provide a device which is simple in nature and structure and which modulates a large amount of power output with good quality modulation 10 by means of a signal of comparatively small power.

A further object of the present invention is to provide a novel scheme and means for impressing on high frequency oscillations phase 15 variations truly representative of the signal so that a good quality modulation is obtained and to accomplish the same by the use of a minimum amount of apparatus operating extremely efficiently. 20

The above objects are obtained in accordance with the present invention by modulating oscillations of constant frequency at the source of production, that is, in the oscillator. For example, if a crystal oscillator is used to produce constant frequency oscillations, modulation may be accomplished in the crystal oscillator. In a crystal oscillator the crystal voltage works into the grid to cathode capacity and a resistive component caused by the grid to cathode current of the tube. This is the input impedance of the tube and, as the grid current is caused to vary by changing the applied grid voltage, that is, by changing the potential applied to the grid of the oscillator at signal 35 frequency, the grid to cathode resistive component varies and the variations produce a phase shift proportional to the variations of the grid to cathode resistance. 30

Any tube that draws sufficient grid to cathode 40 current, so that the resistive component is sufficient, may be modulated in this manner, whether the tube be an oscillator or an amplifier. In a modification of the present invention I provide a new and efficient means for 45 producing phase variations at signal frequency in oscillations repeated in any thermionic relay.

The novel features of my invention have been pointed out with particularity in the claims appended hereto. 50

My novel method of producing phase variations in oscillations which are characteristic of signal currents, and devices for accomplishing the same will be described in detail hereinafter. In this description reference will be made to 55

the drawings, throughout which like symbols indicate like parts, and in which:

Figure 1 shows an arrangement for producing oscillations and for modulating the same as to 5 phase in accordance with my novel scheme;

Figure 2 shows diagrammatically the manner in which phase modulation is accomplished in accordance with the present invention;

Figure 2a is a vector diagram illustrating the 10 manner in which phase shift is obtained in certain voltages in the circuit of Figure 2; while

Figures 1a, 3, 3a, 4, 5 and 6 show modifications of the arrangement of Figure 1.

A specific embodiment of the invention will 15 now be described. In describing said embodiment reference will be made to Figure 1 of the drawings in which, for purposes of illustration, an oscillator and phase modulating means, arranged in accordance with the present invention, 20 have been shown.

In Figure 1 a thermionic tube C has its anode 4 connected as shown to a parallel circuit 6 tuned to a frequency slightly above the frequency it is desired to produce, the circuit 6 25 being inductive in character. The control grid 2 of C is connected to ground by way of a leak resistance 20 and a piezo-electric crystal PC, as shown. Due to the capacity between the electrodes 2 and 4 and the impedance of the 30 tuned circuit 6 oscillations of constant frequency are produced in C and its associated circuits when the electrodes of C are energized. The frequency of the oscillations is determined by the value of the elements included in said 35 circuits, and in particular by the physical dimensions of the piezo-electric crystal PC. The anode to cathode and grid to cathode alternating current circuits are completed by connecting the cathode 8 to ground by way of inductance 40 10, as shown, and by connecting the lower potential terminal of 6 to ground by way of a bi-pass condenser C₁, as shown. The cathode electrode 8 is heated by means of a filamentary heating element and heating circuit which may 45 be energized from any source not shown by way of a transformer 21. To prevent high frequency oscillations from reacting on this transformer each side of the filament heating circuit is connected to ground by way of capacity C₂, as 50 shown. In operation the circuit 6 is tuned to a frequency slightly above the natural frequency of the crystal PC. The external impedance of the plate circuit is high. The resistance 20 furnishes the effective grid bias for the oscillator 55 due to grid rectification. A positive potential may be applied to the anode electrode 4 by way of a tuned circuit 6, which may be connected with the positive terminal of any source of constant direct current potential the negative terminal of which is grounded. The arrangement just described will, as is known, produce oscillations of constant frequency, which frequency will be determined in part by the piezo-electric 60 crystal PC, and in part by the tuned circuit 6. The oscillations so produced may be impressed 65 from circuit 6 on additional apparatus 30, and from 30 to a utilization circuit 32.

The manner in which the oscillations produced in C are modulated in phase at signal 70 frequency will now be described. A source of modulating potentials A as, for example, an alternating current source of constant and audible frequency, or a source of voice modulations or music, impresses potentials at the signal frequency by way of a coupling condenser 16 and

ground to the terminals of a reactor 10. The potentials at signal frequency, appearing across 5 10, are applied to the cathode 8 of tube C. In order that radio frequency oscillations produced in C do not react on the oscillations in the reactor 10 or source A or both, the cathode is connected to ground by way of a radio frequency bi-pass condenser C₁. The condenser C₁ forms a low impedance path by which the radio frequency current may return to the cathode without passing through the modulator, but is of high impedance to the modulating potentials. The potentials applied at signal frequency to the cathode 8 vary the potential of the cathode with respect to the grid electrode 2 and 15 thereby vary the impedance between the grid and cathode of said tube and, consequently, vary the grid to cathode current. Since the crystal voltage is working into the grid to cathode capacity, and the resistive component caused by 20 the grid to cathode direct current, this variation of potential and of current results in a phase shift which is proportional to the variation of the resistive component in the grid to cathode circuit. This in turn phase modulates the current in the anode circuit of the oscillator C so that high frequency oscillations, 25 modulated in phase in accordance with the signal, appear on the anode electrode 4 and are impressed therefrom to the tuned circuit 6. The 30 oscillations so produced and modulated may be passed through an amplitude limiter or a frequency multiplier or an amplifier, or one or more such devices, all of which may be included in the unit 30. The phase modulated os- 35 cillations modified as desired may be utilized in any manner. For example, they may be impressed on a line for transmission or may be impressed, as shown, on an aerial system 32 for radiation. Furthermore, as indicated above the 40 phase modulated oscillations may be further modulated in any known manner before transmission. This modulation may take place any place in the circuits, but preferably takes place after the phase modulation as described above 45 is accomplished.

Although it is thought that the manner in which phase modulation has been accomplished will be understood from the above, a further brief explanation of what takes place in the circuits 50 associated with C to produce phase modulation at signal frequency will be given.

Referring to Figure 2, G represents the quartz crystal input to tube C. The crystal may be considered as a constant voltage generator. We 55 can make such an assumption for the crystal has so much stored energy (circulating current) that there is a persistency of oscillation greater than the audio frequency. If the crystal response curve (resonance curve) is about fifty 60 cycles wide then any audio frequency above that will not effect the output voltage and will not react back on the crystal's frequency of oscillation. This crystal output voltage e₁ is impressed into an impedance network, made up of 65 series elements and shunt elements. For purposes of illustration the series elements may be lumped, and Z represents the lumped series element while R and C represent the shunt elements. R consists mainly of the tube impedance 70 while C is the inter-electrode and inter-circuit capacity. By varying the grid voltage (raising and lowering the cathode voltage) the resistive element of the shunt impedance is varied. The amount of grid current through R and C changes 75.

and this changes the phase of the voltage across R and C and consequently the phase of the grid voltage in accordance with the input tone voltage Er.

In the vector diagram of Fig. 2a, e_1 is the voltage developed by the crystal at G and applied to the network. e_2 is the voltage at the input to the shunt impedances R and C and may represent the voltage applied to the grid of the oscillator for modulation purposes. Z is the impedance of the circuit, the tube electrodes etc. It is the total grid current which flows through Z. I_C is the current which flows through capacity C. I_R is the current which flows through R. I_Z is the potential drop through Z due to current I_R . By mere inspection it may be seen that as we change the input impedance of the tube by varying R, the phase of the grid voltage e_2 is changed. If R is changing, the phase of the network RC is changed, consequently e_2 must change in phase. For example, if R is infinite, a large amount of the current flows through C and the circuit is capacitive and the phase of e_2 is shifted, say ninety degrees relative to the current Z. If R is small, a large amount of the current flows through R and the network is resistive in character and e_2 is in phase with the current through Z. The phase shift and other values given above are not given by way of limitation but are merely for purposes of illustration. The rule holds good for intermediate values of R, as well as the extreme values used. The current vector diagram adjacent the voltage vector diagram in Fig. 2a brings out very clearly how the phase shift is produced, when it is kept in mind that e_1 is constant and that the relative values of R and C change at the modulating frequency. We can get practically linear phase displacement for input tone voltage over a large enough range so that the effective phase swing after multiplication in the doubler stages gives a displacement equal to 100% in amplitude modulation.

Obviously many different types of crystal control oscillators may be used to replace the oscillator shown in Figure 1. Practically any type of piezo-electric controlled oscillator circuit may be used to produce the oscillations which may in turn be modulated in phase in accordance with my novel scheme as illustrated in Figure 1.

For example, an oscillation generator of the type disclosed in Figure 3 may be used to produce constant frequency oscillations of a constant amplitude. This generator comprises a thermionic tube C having its control grid 2 connected, as shown, by way of a grid condenser GC and a tuned circuit 12 to ground. The circuit 12 may comprise capacity and inductance as shown. The anode electrode 4 may be connected to a tuned circuit 6 and to a source of positive potential. The circuit 6 may include inductance and capacity, as shown. The anode electrode 4 may also be coupled to the grid electrode 2 by way of a piezo-electric crystal PC, as shown. Here the cathode 8 is heated in the same manner that the corresponding element is heated in the arrangement of Figure 2. The proper biasing potentials are provided to the control grid 2 due to the flow of rectified grid current in the resistance 20. Due to the impedance of the circuit 6 and to the coupling between the anode and grid electrodes in the tube C and external thereto by way of the piezo-electric crystal PC, sustained oscillations will be produced in the tube C. The frequency of these

oscillations will be determined in part by the circuits 6 and 12 and in part by the natural frequency of the piezo-electric crystal PC.

The oscillations developed are impressed by way of the transformer on to the utilization circuit 32. Here, as in Figure 1, the high frequency oscillations may be modulated at signal frequency by modulating potentials from the source A applied by way of the coupling capacity 16 and choking inductance 10 on to the cathode electrode 8. As pointed out in detail hereinbefore, these modulating potentials vary the impedance between the grid and cathode of said tube and, consequently, work on the grid to cathode direct current. Since the crystal voltage is working on the grid and on the resistive component caused by the grid to cathode direct current, the variations in potential at signal frequency, result in phase shifts of the high frequency oscillations produced in C which are proportional to the amplitudes of the modulating potentials and of a rate equal to the frequency of the modulating potentials.

In both arrangements described the modulating potentials applied from A may represent signals which may be demodulated in a receiver or the modulating potentials from A may be merely for the purpose of improving the efficiency of transmission of the signals. In the latter case the phase wobbled high frequency oscillations may be keyed or otherwise modulated in subsequent stages with intelligible signals. The frequency modulated or wobbled signals may be amplitude limited and frequency multiplied and amplified or amplitude limited and frequency multiplied or amplitude limited, and amplified in the stage 30 and radiated from the aerial 32.

In some cases it may be desirable to modify the arrangements of Figures 1 and 3 as shown in Figures 1a and 3a. Here the parallel tuned circuit 6 has been replaced by a single inductance I. The inductance I may be wound so that, due to its distributed capacity, it will offer a very high impedance to the radio frequency currents. The use of such an inductance also eliminates the necessity of tuning the oscillator at this point. This has a two-fold advantage in that the crystal oscillator may be set and, since there is no tuning in the circuit, the crystal will always oscillate under the same conditions of feedback and with the same voltage impressed on the grid circuit. If the tank tuning is changed, the feedback is changed and the voltage built up on the grid and impressed upon the crystal is also changed. Therefore, I supply a modulating voltage and calibrate the transmitter for a certain percentage modulation and the tank circuit tuning is changed, for example, by the tuned circuits in Figures 1 and 3. The percentage modulation will also be changed. Of course, in practical operation the arrangements of Figures 1 and 3 may be used successfully as it is a simple matter for a trained operator to retune the oscillator and adjust the circuits to produce the desired feedback and percentage modulation. In some cases, however, the modifications of Figures 1a and 3a, wherein the distributed capacity inductance I are utilized, may be preferable.

In practice I use a small thermionic tube C to produce the high frequency oscillations. When the tube is oscillating the rectified grid direct current flowing in the grid leak resistance holds the control electrode of the tube at a certain operating point, which is determined by the circuit constants, such as, plate voltage, feedback

voltage, etc. If, for some reason, the tube should stop oscillating as, for example, on failure of the crystal, the control grid of the tube C would be biased to a point at which a large amount 5 of plate current would flow. This results from the fact that when oscillations cease rectified grid direct current no longer flows in the grid leak resistance and the control grid approaches ground. The high plate current will damage the 10 tube under these circumstances or at least reduce the operating efficiency thereof.

To protect the tube an arrangement as shown in Figure 4 may be used. In this arrangement I place a resistor R_1 in the cathode return of the 15 plate circuit in series with the modulator choking inductance 10. This resistance is of sufficient value to oppose a surge of current in the plate circuit if the oscillator should stop operating and thereby to prevent damage to the tube 20 C under such circumstances. The resistance R_1 , however, is not of sufficient value to have noticeable effect upon the oscillator C and its circuit when the crystal PC is oscillating. This is because when oscillations are produced rectified 25 direct current in the grid circuit builds up in the resistance 20 a high negative bias which is applied to the grid electrode of tube 2 so that said tube, while oscillating, draws but a small amount of plate current. However, when the 30 tube stops oscillating, the plate current at once approaches a much higher value due to the fact that the bias obtained by the grid leak bias elements in the grid circuit becomes lower. This high plate current across the cathode resistor 35 R_1 produces a voltage drop which biases the tube down to a safe value. The tube, therefore, is protected by means of a novel arrangement, which has little or no effect upon the operating characteristics of the oscillation generator.

40 The other features of the circuit of Figure 4 and the operation thereof, by means of which oscillations are produced and modulated in phase at signal frequency, will be understood by inspection of said figure and in view of the detailed description of the prior circuits and the 45 operation of said circuits.

In the arrangements of Figures 1, 1a and 4 production of oscillations is obtained by the nature of the plate circuit, the impedance thereof, 50 and by the capacity between the electrodes in the tube.

In the arrangements of Figures 3 and 3a external coupling between the control grid and anode by way of the crystal PC is provided in 55 addition to the internal couplings and the plate circuit impedance.

Where inductive coupling between the input and output electrodes is desired, arrangements as 60 shown in Figures 5 and 6 may be used. In these arrangements the anode electrode 4 is inductively coupled by inductance 40 with an inductance 41 connected between the grid 2 and the cathode of the tube C. The inductive coupling balances out the capacity feedback in the tube from plate to 65 control grid and offers inductive feedback to the grid circuit so that sustained oscillations are produced. The piezo-electric resonator PC is connected in series with the grid cathode circuit, as shown. To prevent capacitive coupling between 70 the tuned grid circuit and the plate the inductance 40 may be electrostatically shielded from the inductance 41 as shown. In this arrangement the high frequency oscillations produced in the anode circuit feed energy back into the grid circuit to enhance said oscillations. The fre-

quency of the oscillations produced is determined in part by the tuned circuit including the inductance 41 and the parallel variable condenser, and by the crystal PC. The oscillations may be modulated in phase by potentials from the modulating potential source as in the prior arrangements. The phase modulated oscillations may be fed by way of a coupling capacity to the load circuit 32, either directly or by way of a unit 30, which may include an amplitude limiter, a frequency multiplier and an amplifier, and in one or more of said elements.

In Figure 6 the source of modulating potentials is connected by way of a transformer T to the cathode 8 rather than by way of a choking 15 inductance and blocking capacity, as shown in the prior figures. This arrangement may, in some cases, be preferable where the oscillations produced in C are to be phase modulated by telephony signals. The transformer coupling as 20 shown in Figure 6 may, in some instances, give a better incoming characteristic over the various frequencies of the telephony frequency band than may be obtained by the condenser choking method of the prior figures. In some cases 25 means, in addition to the capacity C₁, may be necessary to prevent the high frequency oscillations from reaching the modulation potential source. This means may take the form of a radio frequency choke coil RFC, which may be connected in series between the cathode 8 and the secondary winding of the transformer T by the switches shown. This choking inductance will force the high frequency oscillations to take the shorter path including the capacity C₁.

While I have shown the modulating potentials applied to the cathode and control grid electrodes it will be understood that I contemplate the application of the modulating potentials to the plate electrode, and in case tubes of more than three 40 electrodes are used to the screen grid electrode, or any other appropriate electrode.

Having thus described my invention and the operation thereof, what I claim is:

1. In phase modulated signal producing means, 45 a thermionic vacuum tube having a control grid electrode, an anode and a cathode, frequency determining means connected between the control grid and cathode of said tube, a tunable circuit connected with the anode of said tube to 50 produce oscillations in said tube and said frequency determining means, a leakage path between the grid electrode of said tube and ground, said leakage path including a resistance which determines the potential of said grid electrode 55 relative to ground, a modulating potential impedance connecting the cathode of said tube to ground, and a source of modulating potentials connected to said last named impedance to vary the potential of said cathode relative to ground 60 in accordance with said modulating potentials.

2. In a system for producing high frequency oscillations and for modulating the same in phase, a thermionic tube having an input circuit including, a quartz crystal provided with two 65 electrodes, a connection between one of said electrodes and the control grid of said tube, a connection between the other of said crystal electrodes and ground, a tunable resonant circuit connected between the anode and cathode of 70 said tube for obtaining therein and in said circuits oscillations of a frequency determined by the natural frequency of vibration of said quartz crystal, a source of modulating potentials, a capacity connecting the source of modulating 75

potentials to the cathode of said tube, a modulating potential impedance connecting the cathode of said tube to ground, and an impedance connecting the control grid of said tube to ground.

3. In a system for producing phase modulated high frequency oscillations, a thermionic tube having an anode, a cathode and a control electrode, a piezo-electric crystal connected between 10 said control electrode and ground, a leak resistance connected in parallel with said crystal, a tunable resonant circuit connected between said anode and ground, an inductance connected between said cathode and ground, and a source of 15 modulating potentials connected in parallel with said inductance.

4. In a phase modulated wave signalling system, a thermionic tube having an anode, a cathode and a control electrode, a frequency determining circuit including a piezo-electric crystal connected between the control electrode of 20 said tube and ground, inductive means in a circuit connected between the anode of said tube and ground, an impedance connecting said cathode to ground, a source of modulating potentials connected in parallel to said impedance, and a load circuit coupled to said anode circuit.

5. Signalling means comprising an oscillation generator including, a thermionic tube having 30 an anode, a cathode, and a control grid, a piezo-electric element in circuit with the control grid and another electrode of said tube, an inductance connected between the anode and cathode of said tube, sources of potential for energizing 35 the electrodes of said tube, whereby sustained oscillations are produced in said tube of a frequency determined in part by said piezo-electric crystal and in part by said inductance, means for maintaining the cathode of said tube above ground audio frequency potential, and means for 40 modulating the phase of the oscillations produced including a source of modulating potentials coupled to the cathode of said tube and to ground.

6. In a system for producing high frequency oscillations modulated in phase, a thermionic vacuum tube having a control grid, an anode and a cathode, a piezo-electric crystal in a circuit connected between the control grid and 45 cathode of said tube, a connection between a point on said circuit and ground, an inductance having distributed capacity connected with the anode of said tube to produce oscillations in said tube and said piezo-electric crystal, a leakage path between the grid electrode and cathode of said tube, said leakage path including a resistance which determines the potential of said grid electrode relative to said cathode, and means for varying the potential of 50 the cathode of said tube relative to ground at signal frequency to thereby vary the phase of the oscillations produced.

7. Means for producing high frequency oscillations and for modulating the same in phase 60 comprising a thermionic tube having an input circuit including, a quartz crystal provided with two electrodes, a connection between one of said electrodes and the control grid of said tube, another connection between the other of said crystal electrodes and ground, a tunable resonant circuit comprising parallel inductance and capacity connected between the anode and cathode of said tube for obtaining therein and in said circuits oscillations of a frequency determined 65 by the natural frequency of vibration of said

quartz crystal, a source of modulating potentials, a capacity and a resistance connecting the source of modulating potentials to the cathode of said tube, and an inductance connecting the cathode of said tube to ground.

8. Oscillation producing means comprising, a thermionic tube having an anode, a cathode and a control grid, a frequency determining circuit including a piezo-electric crystal connected with the control grid of said tube, resistive means connecting the control grid to ground, inductive means of considerable distributed capacity connected between the anode of said tube and ground, the inductance and distributed capacity being the sole tuning means for said anode circuit, 10 an inductance connecting said cathode to ground, and a source of modulating potentials connected in parallel to said inductance.

9. Signalling means comprising an oscillation generator including, a thermionic tube having 20 an anode, a cathode, and a control grid, a piezo-electric element in circuit with the control grid and cathode of said tube, an inductance in a circuit between the anode and cathode of said tube, means for regeneratively coupling said circuits, means for energizing the electrodes of said tube, whereby sustained oscillations are produced in said tube of a frequency determined 25 in part by said piezo-electric crystal and in part by said inductance, and means for modulating the phase of the oscillations produced including a source of modulating potentials, a connection between said first circuit and ground, and a transformer having a primary winding connected with said source of modulating potentials and a 30 secondary winding connected at one terminal through an inductance to the cathode of said tube and at the other terminal to ground.

10. Means for producing oscillations and for phase displacing the same in accordance with 40 modulating potentials comprising, a thermionic tube having a control grid, a cathode and an anode, a circuit for heating said cathode, a piezo-electric crystal in a circuit in series with the control grid and with a parallel tuned circuit, 45 the other terminal of which is connected to ground, a grid leak resistance and an additional impedance connected between the control grid and ground, an anode circuit including an inductance and a source of potential connected to the anode of said tube, said inductance being inductively coupled to said tuned circuit, whereby sustained oscillations are produced in said tube and in said circuits, a source of modulating potentials connected between the cathode of said 50 tube and ground, and an impedance in parallel with said source of modulating potentials.

11. In a system for producing phase modulated waves, a thermionic tube having an anode, a cathode and a control grid, a piezo electric 60 crystal connected to said control grid, a reactance connected to the anode of said tube and to the cathode of said tube, said reactance being inductive at the natural frequency of said piezo-electric crystal whereby oscillations are produced in said tube when the electrodes thereof are energized, an impedance connecting the control grid of said tube to ground, an audio frequency reactance connecting the cathode of said tube to ground, and a source of modulating potentials connected to the cathode of said tube and to ground to vary the potential of the cathode of said tube relative to ground potential.

12. In a system for producing phase modu- 75

- lated waves, a thermionic tube having anode, cathode and control grid electrodes, a piezo electric crystal connected in circuit between said control grid and another electrode of said tube, 5 reactive means connected in circuit with the anode of said tube, there being coupling between the control grid and anode of said tube, whereby oscillations are produced in said tube and circuits when the electrodes thereof are energized, 10 a resistance connecting said control grid to ground, and a source of modulating potential connected between the cathode of said tube and ground to vary the potential of said cathode relative to ground at signal frequency.
- 15 13. In a system for producing phase modulated waves, a thermionic tube having an anode, a cathode and a control grid, a circuit connected between the control grid and cathode of said tube, a connection between a point on 20 said circuit and ground, a frequency determining element connected to said circuit, a reactance connected to the anode of said tube and to the cathode of said tube, said reactance being tuned to a frequency slightly higher than 25 the natural frequency of said piezo electric crystal whereby oscillations are produced in said tube when the electrodes thereof are energized, an audio frequency reactance connected between the cathode of said tube and ground, and a 30 source of modulating potentials connected to the cathode of said tube and to ground.
14. In a system for producing phase modulated waves, a thermionic tube having an anode, a cathode and a control grid, a piezo-electric crystal connected in a circuit between said control grid and said cathode, a resistance in parallel with said crystal, a connection between said circuit and ground, a reactance connected with the anode of said tube, said reactance being inductive at the natural frequency of said piezo-electric crystal, whereby oscillations are produced in said tube when the electrodes thereof are energized, an audio frequency reactance and a resistance in series connecting the cathode of 40 said tube to ground, and a source of modulating 45 potentials and a capacity in series connected in shunt to said audio frequency reactance.
15. In a system for producing oscillations modulated in phase in accordance with modulating potentials, a thermionic tube having an anode, a cathode, and a control grid, a piezo-electric element in circuit with the control grid and another electrode of said tube, an impedance connecting the control grid of said tube to ground, a parallel connected inductance and capacity constituting a tunable circuit connected with the anode of said tube, said circuit being adapted to be also connected to the cathode of said tube, means for energizing the electrodes of said tube, whereby sustained oscillations are 15 produced in said tube of a frequency determined in part by said piezo-electric crystal and in part by said tunable circuit, an impedance connected between the cathode of said tube and ground, and a source of modulating potentials connected 20 in shunt to a portion of said impedance to vary the potential of said cathode relative to ground in accordance with said modulating potentials.
16. Signalling means comprising an oscillation generator including, a thermionic tube having an anode, a cathode and a control grid, a piezo-electric crystal connected in circuit with certain of said electrodes to produce definite frequency control, an inductive impedance connecting the anode of said tube to the cathode of said tube and to a source of potential to produce high frequency oscillations in said tube, a leakage path between the control grid of said tube and ground, said leakage path including a 35 resistance which determines the potential of said control grid electrode relative to ground, and means for modulating the phase of the oscillations produced in said tube by varying the input resistance of said tube including a device for 40 applying signal potentials between the cathode of said tube and ground to vary the potential of said cathode relative to ground at signal frequency.

HALLAN EUGENE GOLDSTINE. 45
